SCALP AIR COOLING SYSTEM FOR PERMANENT HAIR WAVING

Joseph Zoberg, West New York, N. J.

Application December 20, 1934, Serial No. 758,347

4 Claims. (Cl. 132—36)

This invention relates to new and useful improvements in a scalp cooler system for permanent hair waving.

The invention may best be understood by first considering present day methods of permanent hair waving. The chief method consists in wetting the hair with a wave lotion and then winding the hair on curlers arranged in rows or otherwise upon the scalp, and finally applying heat to the curls with a suitable mechanism. The chief defects of the present day systems reside in the danger of burning the scalp due to steam being generated when the hair lotion evaporates under the heat supplied. The curlers are insulated from the head by the use of suitable felt pads and rubber protectors, but in spite of these precautions, the steam very often reaches the scalp and causes burns. Certain person's scalps are more sensitive than others and burn more readily. Such persons usually cannot take the permanent wave treatment without certain damage. Furthermore, the heat generated is uncomfortable to bear.

The invention has for an object the provision of a mechanism for cooling the head so as to make the treatments pleasanter, and furthermore proposes the blowing of air against the scalp to dissipate any steam which may reach the scalp.

Still further the invention proposes the provision of a plurality of hollow fingers adapted to be placed along the scalp while the permanent hair waving apparatus is on the head, and equipped to direct cooled air against the scalp and beneath portions of the hair waving equipment.

A further object of the invention is the provision of an arrangement wherein the edges of the felt pads, usually used in permanent hair waving, are raised in such a manner that the directed air from the fingers may readily enter therebeneath.

Another object of the invention is the construction of a device as mentioned which is simple and durable and which can be manufactured and sold at a reasonable cost.

For further comprehension of the invention, and of the objects and advantages thereof, reference will be had to the following description and accompanying drawings, and to the appended claims in which the various novel features are more particularly set forth.

In the accompanying drawings forming a material part of this disclosure:

Fig. 1 is a plan view of the curl portion of a permanent hair waving device in conjunction with which the invention is used.

Fig. 2 is a plan view of a portion of Fig. 1 showing a certain clamp in an opening position.

Fig. 3 is a perspective view of one of the heaters adapted to be used in conjunction with the curl device illustrated in Fig. 1.

Fig. 4 is a top plan view of a person's head, showing the application of the clamps and the cooling pipes.

Fig. 5 is a plan view of one form of apparatus according to this invention.

Fig. 6 is a side elevational view of the device taken on the line 6—6 of Fig. 5.

Fig. 7 is a fragmentary sectional view looking in the direction of line 7—7 of Fig. 4.

Fig. 8 is a perspective view of a portion of one of the felt pads used in the device.

Fig. 9 is a fragmentary enlarged view of one of the fingers of the device.

Fig. 10 is a sectional view taken on the line 10—10 of Fig. 9.

Fig. 11 is a similar view to Fig. 10, but illustrating a modified form of the invention.

Fig. 12 is a fragmentary plan view of the device shown in Fig. 6.

Fig. 13 is an enlarged vertical sectional view taken on the line 13—13 of Fig. 12.

Fig. 14 is a longitudinal sectional view taken on the line 14—14 of Fig. 13.

Fig. 15 is an enlarged view of a portion of Fig. 14.

Fig. 16 is a perspective view of the device embodying a modified form of the invention.

Fig. 17 is a side elevational view of the device as illustrated in Fig. 16.

Fig. 18 is a plan view of Fig. 17.

Fig. 19 is a similar view to Fig. 5, but showing a modified form of the invention.

Fig. 20 is an elevational view of Fig. 19 taken on the line 20—20 of Fig. 19.

Fig. 21 is a perspective view of another form of hair waving device showing the application of the invention.

In Fig. 4, the head 10 of a person is shown in elevation to which a plurality of curling devices 11 are shown applied. In the art of permanent hair waving these devices are arranged in parallel rows or otherwise. Each of these devices comprises a clamp, as shown in Fig. 2, used in conjunction with a felt pad 12. The clamp comprises a stationary portion 13, a hinged portion 14, and a lock 15 adapted to tightly press the hinged portion against the stationary portion. The hinged portion 14 is equipped with a covering of rubber, or similar soft material, and acts against soft material on the stationary portion. The

felt pad 12 is formed with a central slit 16 (see Fig. 8) through which the hair may be threaded.

The curling device is also equipped with a holder 18 in which a rotative curler 17 is mounted.

The curl is produced by first grouping the hair together in small groups, passing one of the groups through the slit 16 of one pad, and forcing the pad tightly against the scalp. The clamp is then closed by forcing the movable portion against the stationary portion, and closing the latch 15. The strand of hair is then wound upon the curling device 17 which is set upon the clamping device. A heater 20 is then engaged over the hair on the curler 17. Thus far, a particular type of permanent hair waving device has been described. The commercial types are practically all the same, merely differing in the locations and designs of the various parts thereof. For example, certain devices have different types of heaters; others have different types of curlers, etc. In all of the devices the heaters are connected by electric wires or by steam pipes to a stand from which there extends a main cable to an electric plug, or source of power or heat.

The invention consists in apparatus which includes a plurality of hollow fingers 21 adapted to be extended over the scalp and between the lines of curling devices. These fingers are of flexible material, if desired pliable, and formed with staggered side apertures 22 located at opposite sides, near the bottom sides thereof, and arranged to direct air against the scalp.

In the form of the device illustrated in Fig. 5, the fingers 21 connect with a swivelled distributor 23 which has a main inlet 24 connected with an outlet 25 of an air supply line 26. The distributor 23 has a flared end 23^b rotative between a pair of fixed flanges 23^a; this construction being such that the distributor may swivel. This air supply line is stationary and is mounted along the wall or floor of an establishment. It connects with a compressor 27. The pipe line 26 is provided with a plurality of outlets 25 which are normally closed with plugs and to which the distributor 23 may be connected. The function of the construction is such that the distributor 23 may be connected up with any one of the outlets 25 so that the device may be in the vicinity of the person worked on.

In this form of the invention the device is portable. The distributor 23 is mounted upon a stand 32 having casters 33 by which it may be pushed around. A motor driven blower may also be mounted upon the platform 32 for supplying the air into the distributors 23 independent of the air supply line 26. A plurality of branch fingers 21 extend from the distributors 23 as previously described.

Each of the fingers 21 has a track element 34 extended along the top upon which snap fastener elements 35 are adjustably mounted. The bottom sides of the felt pads 12 are equipped with complementary snap fastener elements 36.

When the fingers 21 are extended over the scalp, they are connected with the pads by engaging the snap fastener elements 35 and 36. The elements 35 are moved along in the track 34 to be in aligned positions for the connections.

The arrangement is such that when the edges of the pads 12 connect with the top sides of the fingers 21, the apertures 22 will be in line to blow beneath the raised edges of the pads. In Fig. 8 a pad is illustrated with its edges raised. In Fig. 7 a transverse cross section is shown in which

one of the openings 22 of the fingers is clearly shown in line to discharge its air beneath the pad.

In Fig. 11 the fingers 21' are shown to be in oval cross section with flattened sides.

In Figs. 12 to 15 a means is indicated for attaching the fingers 21 to the distributor 23. This means includes a distributing head 23' removably engaged on the end of the distributor 23 and is adapted to receive eight threaded bushings 23^d which support nipples 23^b, see Fig. 15, clamped in position by glands 23^c. Instead of eight bushings 23^d and nipples 23^b any other number of these members or similar parts may be provided for connecting with fingers 21.

One of the fingers, indicated by reference numeral 21^a is equipped with a discharge head 38 having a plurality of apertures for the discharge of a stream of air, as schematically shown at 39. The distributor 23 is equipped with a main control valve 37 and a plurality of subcontrol valves 37' to control the air in the individual fingers 21 and 21^a.

In Figs. 16 to 18 a housing 32' is shown mounted on stand 32. In the housing 32' there is a blower 32^a which is separated from its driving motor 32^b by a partition 32^c. The intake of the blower is indicated at 32^d and a distributor 23 is mounted at the exhaust. This distributor is equipped with fingers 21 as previously described. In Figs. 19 and 20 the distributor 23 is shown swivelly mounted by the flared end 23^b on the flanges 23^a of vertical pipes 23^b which are connected to the pipe line 26 through outlet 25 as previously described.

The operation of the device is as follows: The head of a person is set up with the permanent hair waving apparatus as is now customary in the trade. When the apparatus is properly in place, the cooling device should then be set into position before the heat is turned on. The setting of the cooling device into position consists in placing the flexible fingers 21 in the paths formed between the strands of hair which are engaged in curls upon the curling device. These fingers are held in position by the engagement of the snap fastener elements 35 and 36 with each other.

After the fingers of the air supply cooling system have been mounted throughout the scalp of a person, the hair waving device is set into operation by turning on of the mechanism controlling the heat. The air of the cooling device is then turned on. The cool air will strike against the scalp and serve to dissipate the heat which is radiated from the heating apparatus of the waving device. Furthermore the air will reach the scalp beneath the felt pads 12 and so blow away and dissipate any steam which may be generated in the curls of hair and which may pass downwards through the clamping apparatus shown in Fig. 2 and slit 16 of the felt pad.

The clamp portions 13 and 14 in Figs. 1, 2, and 7 are hollow and are provided with air supply connecting nipples 13' and 14' respectively. These nipples may be connected to a suitable air supply line for blowing air through apertures 13^a and 14^b of the clamp portions 13 and 14 respectively. This arrangement of supplying an air cooling blast to dissipate any steam which may be generated may be used in place or in conjunction with the previously described supply.

In Fig. 21 a spiral type of heater 20' is illustrated slightly raised from operating position. With this heater, the curler rod 17' is held in vertical position and one of its ends is engaged between the usual pivoted clamp members 13^b

and 14^b. Split felt pad 12' is interposed between the said clamp members and the bottom felt pads 12^a. The latter are provided with snap fastener members 36 adapted to engage with snap fastener members 35 of fingers 21.

It is to be understood that the fingers 21 and finger retaining nipples 23^b may be secured on the distributor head 23' in circular arrangement, in rows of two or more or in any other desired manner.

While I have illustrated and described the preferred embodiment of my invention it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. In a device of the class described, a plurality of flexible hollow tubular fingers with passages for directing air against the scalp, and means for holding said fingers in position upon the head, while a permanent hair waving apparatus is mounted on the head ready for use, comprising adjustably mounted snap fasteners upon the fingers and engageable with complementary snap fasteners on portions of the hair waving apparatus on the head.

2. In combination with a permanent hair waving apparatus when upon the head ready for use and including felt pads conformable to the scalp and beneath a curling device, a plurality of flexible hollow tubular fingers with passages for directing air against the scalp and beneath said pads, snap fastener elements upon the sides of said pads, other snap fastener elements adjustable along the lengths of said fingers and connectable with said first mentioned snap fastener elements.

3. In a device of the class described, a plurality of flexible hollow tubular fingers with passages for directing air against the scalp, and means for holding said fingers in position upon the head while a permanent hair waving apparatus is mounted on and conformable to the head, comprising coacting holding elements on the fingers and on portions of the hair waving apparatus on the head, the holding elements on one of said parts being movably mounted for coaction with the holding elements on the other of said parts.

4. In a device of the class described, a cool air supply mechanism including a portable base, a motor driven fan mounted thereon, a cool air supply line from said fan, and a plurality of flexible fingers connected with said supply line and adapted for engaging along areas of the scalp and having apertures for discharge of air against the scalp, said flexible fingers having apertures through which cool air is forced for cooling the scalp, and means for holding said flexible fingers in an adjusted position so that the said flexible fingers extend over the scalp portion of the head and in the paths formed between the strands of hair.

JOSEPH ZOBERG.
